UNITED STATES PATENT OFFICE.

ROBERT J. CROSS, OF MAYFIELD, CALIFORNIA.

BOOKBINDING.

Application filed December 13, 1921. Serial No. 522,195.

To all whom it may concern:

Be it known that I, ROBERT J. CROSS, citizen of the United States, residing at Mayfield, in the county of Santa Clara and State 5 of California, have invented a new and useful Bookbinding, of which the following is a specification.

The present invention is a note cover and binder for loose leaves or sheets of paper.

10 In note books or covers, of which applicant is aware, when opened flat on a table or desk, the leaves thereof close or tend to turn back over the hand of the writer from the pressure of the hand resting on the 15 opened book. It is the usual practice to turn some of the leaves back under the book or to apply pressure on the two open sections of the book to maintain them in open position when writing.

20 It is the object of the present invention to produce a loose-leaf note-book or cover, which will open in such a manner that, when laid flat on a table, or used as a field or hand-book, the leaves thereof will not close, and to 25 produce a cover in which one or a plurality of loose leaves may be bound and which will permit the readily and easy removal of any 30 number of leaves or intermediate leaves without necessitating the removal of the other leaves from the cover.

35 The invention further resides in the sundry details of construction, combination and arrangement of parts hereinafter more fully described and pointed out in the appended claims.

40 In this specification and the annexed drawings, the invention is disclosed in the form in which it is considered to be the best, but the invention is not limited to such form 45 because it is capable of being embodied in other forms; and it is to be understood that in and by the claims, following the description herein, it is intended to cover the invention in whatever form it may embody within the scope thereof.

50 In the drawings which illustrate the preferred embodiment of the invention as at present devised,

Figure 1 is a side elevation of the book in its closed position.

55 Figure 2 is a side elevation of the book in open position and illustrating the same used as a field or note-book.

Figure 3 is a side view showing the book 60 open to lie flat upon the desk, and

Figure 4 is a side view showing the book

open with certain of the open leaves turned back under the book.

Figure 5 is a fragmentary detail sectional view taken longitudinally through the book 60 or tablet, showing one manner in which a cover section and book leaves can be secured together.

Referring particularly to the drawings, in which like characters refer to corresponding parts throughout the several views and in the specification, the invention comprises a front or upper cover 1 and a relatively thicker back or tablet portion 2 both, preferably, 65 rectangular in shape and of rigid material. 70 To the one edge of the tablet portion is hinged, as at 3, a binder block 4 which is preferably co-extensive with the said edge and has the same relative thickness as the 75 body of the tablet 2, for the purpose which 80 will later appear. The cover 1 is flexibly connected at 5 to a binder strip 6 corresponding to the binder block 4. The binder strip and binder block lie opposite and parallel 85 to each other and are equipped with means 90 for binding loose leaves or sheets of paper therebetween. The back 2 is cut away or morticed inwardly from the upper edge thereof to provide a recess 7 in its outer face 95 extending transversely thereof. This recess is of sufficient depth to accommodate binder block 4 when the book is opened as shown 100 in Figs. 2, 3 and 4.

By virtue of this construction it is clear 105 that, when the book is open, the bound edges of the leaves are moved to and retained at right angles with respect to the back or tablet portion 2 of the cover, the result being that the leaves will not and do not tend to close upon the hand of the writer when the ordinary pressure is applied to the book during the writing operation. It is also clear 110 that on account of the angular formation of the binder block 4 which is received in the recess 7, that the opened position of the leaves is insured to a greater degree as the pressure of the hand during writing increases, by virtue of an angular surface of the block engaging with the table or the like, this being contrary to performance of 115 the ordinary book or binder as above set forth. However, no pressure is required to insure the opened position of the leaves as the binder block is loosely hinged at 3 and is of such thickness as to correspond to 120 the depth of the recess in the back 2 so that when received in the recess 7, the entire 125

back or tablet 2 may lie flat upon a table or desk, and the block 4 prevented from moving on account of its angular formation.

In the use of the invention as a field book, 5 as shown in Fig. 2, the block 4 will move into the recess 7 and remain in that position by reason of the weight of the hanging or opened leaves α . In this position, as in the 10 instance above, there is no tendency for the opened leaves α to close during the writing operation. To permit the opened leaves α to be turned back underneath the book, as 15 shown in Fig. 4, the cover 1 of the book is hinged or flexible transversely at the point 8, the distance between the hinged or flexible portions 5 and 8 being of slightly greater width than the binder strip 6 in order to permit this folding of the book and leaves.

The parts 1, 2, 4 and 5 may be all covered 20 by a covering of cloth, leather or other suitable material and the hinged members 4 and 6 are to be concealed by the covering in such manner as to prevent any liability of scratching or otherwise marring a desk, 25 table or the like.

The means for binding the leaves between the cover 1 and back 2 of the note-book may be of any suitable character; one form of 30 this means being shown and described in my Patent 1,424,622 granted August 1, 1922. However, in Figure 5 one form of binding means is shown consisting of a threaded rod 16 pivoted to the strip 6 at an intermediate point of the latter and having a thumb 35 nut 17 threaded thereon. The block 4 is formed with a pocket b having slots c and d , the slot c being of such width as to receive the threaded rod 16 and provide a shoulder against which the end a of the 40 nut may engage, the slot d providing an opening for the end e of the nut to move through when adjusted. The block 4 and the back 2 of the book are preferably of the same thickness in order to permit the 45 book to lie flat upon a flat surface.

Having thus described the invention, it is to be understood that certain changes in the construction, combination and arrangement of parts may be made which fall within the 50 scope of the appended claims.

I claim:

1. In a note-book of the kind described, a tablet member, a binder member hingedly connected to an edge of the tablet member, 55 means for binding leaves to said binder member, said tablet member having a recess in one side thereof adjacent said binder member and into which said binder member is received when the leaves of the book are 60 opened.

2. In a note-book of the kind described, a substantially rigid tablet member, a binder member hingedly connected to an edge of the tablet and of the same relative thickness 65 of said tablet, means for binding leaves to

the front face of said binder member, said tablet having a recess in its outer face or back extending inwardly from said edge thereof and into which said binder member moves when the leaves of the book are 70 opened, said means lying wholly within said recess when the leaves are fully opened, whereby the tablet will be flat on a flat surface with the binder member received in 75 said recess.

3. In a note-book of the kind described, a substantially rigid tablet member, a binder member hingedly connected to an edge of the tablet and of the same relative thickness 80 of said tablet, means for binding leaves to the front face of said binder member, said tablet having a recess in its outer face or back extending inwardly from said edge thereof and into which said binder member moves when the leaves of the book are 85 opened, said means lying wholly within said recess and having an angular face adapted to lie flush with the outer face of the tablet member, when the leaves of the 90 book are opened.

4. In a note-book of the kind described, a substantially rigid tablet member having a transverse recess in its outer face adjacent an edge thereof and extending inwardly from said edge; an angular binder member hingedly connected to said edge of the tablet and having the same relative thickness 95 of said tablet and having its width corresponding to the depth of said recess, means for binding leaves to the inner face of said binder member, said binder member being movable into said recess, when the leaves of the book are opened, having an angular face thereof to lie flush with the outer or back 100 face of the tablet portion.

5. In a note book of the character described comprising two cover sections, one of said cover sections having a transverse recess in its outer face adjacent an edge thereof and extending inwardly from said edge; a leaf binder means including a strip co-extensive with said edge of said cover section and hingedly connected thereto, said strip having the same relative thickness of 110 said tablet portion and having its width corresponding to the depth of said recess, a complementary strip co-extensive with a corresponding edge of the other section, and means between said strips for maintaining them in binding relation; the strip of said 115 first cover section being receivable in the recess thereof when the leaves of the book are opened; said other cover section being flexible transversely, intermediate its edges with the portion between the binder means and said flexible portion thereof of a width corresponding to the width of said binder means.

6. In a book binding of the kind described, two cover sections, a binding portion at one 120

of the edges of said sections for binding the leaves therebetween, one of said cover sections having means to receive the binding portion when it is folded back under said 5 cover section, said binding portion having a flat surface thereon adapted to engage the surface of a table, desk or the like when said sections are open, whereby said binding portion is prevented from moving relative 10 to said cover section when pressure is applied on either of said cover sections while lying on the table or the like, and a tendency of the open leaves between the sections to close, when said pressure, is removed.

15 7. In a bookbinding of the kind described, two cover sections having means for binding leaves therebetween at one of their edges, at least one of said sections having a recess adjacent the binding means into which a 20 portion of the bound edge of the book en-

ters, when the sections are opened and having a relatively flat surface to engage with the surface of a desk, table or like support when the binding means has entered the recess, for the purposes set forth.

8. In a book binding of the kind described, two cover sections having means for binding leaves therebetween at one of their edges and hingedly connected to said sections, at least one of said sections having a pocket adjacent the binding means, said pocket being positioned in the cover section whereby the binding means is retained in said pocket when said pocketed cover section is lying on or engaged by a relatively flat surface and 30 the cover sections are opened.

In testimony whereof I have hereunto set my hand.

ROBERT J. CROSS.
